US00D566503S

(12) **United States Design Patent** (10) **Patent No.:** **US D566,503 S**
Leasure (45) **Date of Patent:** **** Apr. 15, 2008**

(54) **SANDER**
(75) Inventor: **Jeremy D. Leasure**, Jackson, TN (US)
(73) Assignee: **Black & Decker Inc.**, Newark, DE
(US)

(**) Term: **14 Years**

(21) Appl. No.: **29/288,466**

(22) Filed: **Jun. 12, 2007**

(51) **LOC (8) Cl.** **08-01**
(52) **U.S. Cl.** **D8/62**
(58) **Field of Classification Search** **D8/67, D8/62, 61; D32/15, 17, 19; D4/102; 451/456, 451/451, 359, 358, 357, 356, 355, 354, 353, 451/351, 344**

See application file for complete search history.
